**ROOF CONSTRUCTION FOR A BUILDING
STRUCTURE****William Seibert, Haddonfield, N.J., assignor to The
Frostie Company, Camden, N.J.****Filed Mar. 20, 1972, Ser. No. 236,575****Term of patent 14 years****Int. Cl. D25—02****U.S. Cl. D13—1 R**FIG-2

FIG-3

FIG. 1 is a perspective view of a roof construction for a building structure, embodying my novel design;

FIG. 2 is a front elevational view of the roof construction illustrated in FIG. 1;

FIG. 3 is a side elevational view of the roof construction illustrated in FIG. 1, the opposite side thereof being substantially identical therewith; and

FIG. 4 is a rear elevational view of the roof construction illustrated in FIG. 1.

The broken lines in the drawings are for illustrative purposes only and form no part of the claimed design.

I claim:

The ornamental design for a roof construction for a building structure, substantially as shown and described.
